FRONT LOADING EXTENSION LADDERS

Lawrence A. Kocina, Simsbury, Conn., assignor to R. D. Werner Co., Inc., Greenville, Pa., a corporation of Pennsylvania

Filed June 23, 1965, Ser. No. 466,241
5 Claims. (Cl. 182—209)

This invention relates to extension ladders and relates more particularly to ladders of such type wherein the sections thereof may be detached or separated, and employed as separate ladders.

It is an object of this invention to provide an extension ladder of the type referred to wherein the separation of the respective sections thereof may be accomplished while the ladder is in its inclined or working position.

It is a further object of this invention to provide the respective sections of the extension ladder with guide members guiding the said sections for longitudinal movement with respect to each other, said respective guide members providing easy front loading of the ladder and ready disengagement of the sections when desired.

A still further object of this invention is to provide an extension ladder of the type referred to, in which both of said sections are capable of being used as individual single ladder units and which can each be provided with end caps and ladder feet.

Another object of this invention is to provide improved guide means for an extension ladder of the type referred to. Yet another object is to provide improved means for disengaging the respective ladder sections of an extension ladder.

Another object of this invention is to provide an improved extension ladder of the type referred to which will be economical in construction and highly efficient in use.

These and other objects of this invention will become more readily apparent from a purview of the invention as set forth in the appended description and disclosed in the drawings in which:

FIG. 1 is an exploded side view of the base and fly sections of the front loading extension ladder of this invention.

FIG. 2 is a front elevation of the fly section only.

FIG. 3 is a front elevation of the base section only.

FIG. 4 is a side view showing a first step in assembling the fly section to the base section; this view also shows the last step in disassembling the fly section from the base section.

FIG. 5 is a side view showing the fly section completely assembled to the base section but not extended.

FIG. 6 is a side view showing the fly section assembled to the base section and fully extended.

FIG. 7 is a fragmentary front elevation of one side rail of each section, partly broken away, as viewed from the line 7—7 of FIG. 5.

FIG. 8 is a view similar to FIG. 7 but viewed from the line 8—8 of FIG. 4.

FIG. 9 is a side view of an upper end portion of one ladder section rail.

FIG. 10 is a top plan view of the rail of FIG. 9.

FIG. 11 is a transverse section taken along the line 11—11 of FIG. 7.

FIG. 12 is a transverse section taken along the line 12—12 of FIG. 7.

FIG. 13 is a diagrammatic view combining views similar to FIGS. 11 and 12 but showing modified ladder rails.

Referring now to the drawings in all of which like parts are designated by like reference characters, and particularly to FIGS. 1-5, the front loading extension ladder of this invention is generally indicated at L and comprises a fly section 20 and a base section 40. The fly

2

section 20 comprises a pair of channel shaped side rails 21 having webs 22 and laterally outwardly directed, parallel flanges 23, having inturned end portions 23', as best shown in FIGS. 11 and 12. The upper end of each rail 5 21 is surmounted by an end cap 24 (see FIGS. 7, 8, 9), and the webs 22 are connected by rungs 25 in a conventional manner.

The inner surface of each web 22 of the side rails 21 of the fly section is provided with a catch member 26 pivoted to said web by suitable means, such as brackets 27 carried by the said web. Each catch member 26 is of inverted J-shaped form having an open-end slot or cut-out 26a, adapted to engage adjacent rungs of each of the ladder sections to secure said sections in any desired extended position; a pivoted retainer arm 26b automatically locks the same in position. The catch members, as shown, are preferably mounted on the lower sides of the fly section, as for example, just above the third rung of the same, wherefor the catches engage the third rung of the fly 10 section and simultaneously a corresponding rung of the base section 40 disposed adjacent thereto when the ladder sections are assembled and in the non-extended position of FIG. 5.

The lower end portion of each rail 21 of the fly section 25 20 carries a lower guide bracket 28 which projects laterally outwardly from the fly section 20, as well shown in FIG. 2, for engaging and entering a side rail of the base extension 40, in a manner to be hereinlater fully described.

30 The base section 40 of the ladder comprises channel shaped side rails 41 having webs 42 and laterally inwardly directed, parallel flanges 43, having inturned end portions 43'. An end cap 44 is secured to the upper end of each rail 41, and the webs 42 are connected by rungs 45 in a conventional manner.

Pivoted ladder shoes 46 are carried by the lower ends of the rails 41, said shoes being pivotally mounted upon laterally directed bolts 47 extending transversely of the rails 41. The bolts 47 are disposed through a slot 47a 40 in the web 42 of the rail 41 whereby the shoe may be rotated outwardly of the rail to clear the guide means on the fly (see FIGURE 8). The said pivotal mounting of the ladder shoes 46 permits the ladder to be solidly footed upon a ground or base surface B, shown in broken lines in FIGURES 4-6, even though the ladder be angled against a wall or other vertical surface V, also shown in broken lines in said figures of drawing.

An inwardly directed, upper guide bracket 48 similar to the fly section bracket 28 is carried at the upper end 50 of each of the side rails 41 of the base section 40, and said guide brackets are adapted to engage and enter the side rails 21 of the fly section 20 in a manner to be hereinlater fully described.

It will be noted that the rails 21 of the fly section 20 55 are so laterally spaced as to loosely and slidably fit between the side rails 41 of the base section 40 and that the rungs 45 of said base section are disposed below or behind, as shown, the front flanges 43 whereby the fly section 20 can nest partially within the base section 40.

60 This nesting allows the lower guide brackets 28 to project behind the front flanges 43 of the base section 40 and the upper guide brackets 48 to project behind the front flanges 23 of the fly section 20.

Referring now to FIGURES 7-10, the end caps 24 on 65 the fly section 20 and the end caps 44 on the base section 40 are identical in form although relatively oppositely positioned on their respective ladder section. Therefore, only the end caps 24 will be described in detail, and it will be understood that the end caps 44 comprise like 70 parts.

Each end cap 24 comprises an upright web 30 and an upwardly arched, laterally offset hood 31 providing an

upwardly rounded surface extension of the flanges 23 of the associated rail 21. Each web 30 is adapted to be disposed in general alignment with the web 22 of the associated rail, and the lower end of each said web 30 has a pending mounting extension 32 which has a vertical slot 33 disposed therein for receiving the upper edge portion of the associated rail web 22. Vertical reinforcing gussets 34 are provided on the outer side of each web 30 beneath the laterally offset hood 31, said gussets extending downwardly to the bottom edge of the mounting extension 32. Said end caps are secured to the ladder rails 21 by means of rivets 35 which project laterally through the mounting extensions 32 and the associated rail webs 22.

The end caps 44 are positioned laterally opposite to the end caps 24 and comprise, briefly, upright webs 50, arched hoods 51, depending mounting extensions 52 having slots 53, reinforcing gussets 54, and fastening rivets 55. The hoods 51 are laterally offset outwardly of the base 40, as best illustrated in FIGS. 7 and 8. By positioning the hoods 31 and 51 to be laterally offset in opposite directions, adequate clearance is provided at the tops of the rails 21 and 41 to permit disengagement of the fly section 20 from the base section 40. The offset of the end caps of each ladder section permits said end caps to clear the side rails of the other section, and the offset of the end caps 24 provides clearance for the upper guide brackets 48. The end caps may be made of any suitable material such as plastic or aluminum, and may be manufactured by any suitable method such as injection molding or casting.

As herein illustrated, channel shaped ladder shoes 46 are disclosed (FIGS. 7 and 8) on the feet of the base section and are formed to provide a horizontal base 60 having cleats or ribs 61 secured thereto by means of rivets 62. V-shaped integral arms 63 and 64 project upwardly and are offset inwardly to be pivoted upon the bolts 47. The upper end of each arm 64 carries a laterally projecting tongue 65, the end of which abuts the inner surface of the web 42 of the associated side rail 41 of the base section to maintain preferred spacing between said arm 64 and the arm 63. Shoes may be provided on both the fly and base sections, if desired.

The guide brackets 28 and 48 are identical in form but are oppositely positioned in the side rails 21 and 41, respectively, as well shown in FIGS. 11 and 12. Said guide brackets 28 and 48 comprise, respectively, flat mounting portions 36 and 56, laterally outwardly and inwardly projecting slide portions 37 and 57, and backwardly turned ends 38 and 58 carried at the distal edges of said slide portions. As illustrated, the slide portions 37 and 57 extend behind the flanges 43 and 23 having inwardly turned hooks 43a and 23a which engage or hook over the ends 38 and 58, respectively. Rivets 39 and 59 secure the mounting portions 36 and 56 to the inner surfaces of the webs 22 and 42, respectively, with the slide portions 37 and 57 positioned adjacent the associated rail flange which overlaps the opposite ladder section. From the foregoing it will be readily seen that when the lower guide brackets 28 are hooked behind the front flanges 43 and the upper guide brackets 48 are hooked behind the rear flanges 23, the fly section 20 and base section 40 can be moved longitudinally with respect to each other from the retracted position of FIG. 5 to the extended position of FIG. 6 while remaining positively engaged with each other.

To initially engage the fly section 20 to the base section 40, said sections are positioned generally as shown in FIG. 4 with the base section leaning against a vertical surface V. The fly section 20 is then manipulated whereby the upper ends of the side rails 21 are slightly below the upper guide brackets 48 of the base section 40 and whereby said side rails 21 are resting on the top rung 45. A slight upward movement of the fly section 20 then causes the flanges 23, adjacent the top rung 45 of the base

section to slip behind the slide portions 57 of the upper guide brackets 48. At the same time, the lower end of the fly section 20 is moved inwardly against the rungs 45 whereby upward movement of the fly section causes the slide portions 37 of the lower guide brackets to engage the front flanges 43 of the base section side rails 41. By use of the catch member 26 in the conventional manner, the fly section 20 may be maintained in any desired extended position as, for example, that shown in FIG. 6.

It will be readily understood that removal of the fly section 20 is effected by reversing the above described operation. Interference between the ladder shoes 46 and the lower guide brackets 28 can be avoided by pivoting said shoes away from the fly section 20, if necessary. It will be further noted that the ladder sections may also be engaged or disengaged by laying the base section upon the ground with the fly section overlying it whereby the guide brackets and rail flanges will engage or disengage upon longitudinal sliding movement of the fly section. However, a particularly advantageous feature of this invention is the ease with which the extension ladder can be manipulated while in an inclined or working position.

FIG. 13 shows a diagrammatic view of a pair of modified side rails 71 and 91 comprising fly and base sections 70 and 90, respectively. In this modification, the rails are I-shaped, having flanges 73 and 93 which project on either side of webs 72 and 92, respectively. It will be noted that guide brackets 75 and 95 similar to guide brackets 28 and 48 previously described can be carried on one side of the I in substantially the same manner as the guide brackets 28 and 48 are carried by the rails 21 and 41, respectively, in the form of FIGS. 1 to 12.

It will be understood that many other changes in the details of the invention as herein described and illustrated may be made without, however, departing from the spirit thereof or the scope of the appended claims.

What I claim is:

1. In a device of the class described, a pair of ladder sections, one a fly section and one a base section, said sections including channel-shaped side rails and connecting rungs, said channel-shaped side rails having substantially parallel flanges, said flanges having inturned end portions, means for guiding said sections mounted internally of the channel of the rails of each section for parallel sliding and longitudinal movement with respect to the other section, said guide means having an outwardly projecting side portion having hooked ends, said ends hooking over the inturned ends of the rail flange of the opposite ladder section, the guide means on the fly section extending laterally of the channel-shaped rail of said fly section engaging the channel-shaped rail of the base section, the flanges of the channel of the fly section being disposed outwardly of the web thereof and the flanges of the channel of the base section being disposed inwardly of the web thereof facing the flanges of the fly section and spaced therefrom by the said guide means.

2. In a device of the class described in claim 1, each of said guide means carried by the fly section and the base section rails being of angular form having a relatively longer leg portion secured to the web of its associated rail and a relatively shorter leg portion extending laterally of the web and slidably disposed within a flange of the opposite rail section.

3. In a device of the class described in claim 1, end cap members secured to the upper end of the rails of said base section, said caps each comprising a portion secured to the outer face of the web of said rails and a hood portion extending laterally outwardly therefrom, and other end cap members secured to the upper end of the rails of said fly section, said other caps each comprising a portion adapted to be secured to the inner face of the web of said rails and a hood portion extending laterally inwardly therefrom.

4. In a device of the class described in claim 1, end cap members secured to the upper ends of the rails of the

fly and base sections, said caps comprising a portion secured to the web of said rails and a hood portion extending laterally and inwardly therefrom, wherefor the end caps of the fly section clear the guide means on the base section and the end caps of the base section clear the side rails of the fly section during disassembly and assembly of the sections.

5. In a device of the class described in claim 1, shoes comprising channel-shaped shoe members adjustably and pivotally secured to the ends of the side rails of the base section, the web of the channel of each said shoe being disposed in spaced relation to the bottom of the rail and being rotatable to afford clearance for the said guide means mounted on the bottom of said fly section to permit disengagement by the guide means with the lower portion of the base section and outward movement thereof of said

10

15

fly section, further downward movement of the fly section permitting disengagement of the upper portion of the fly section by the guide means mounted on the upper portion of the base section.
